(57) **CLAIM**

The ornamental design for an offset filter housing, as shown.

DESCRIPTION

FIG. 1 is a perspective view of an offset filter housing, showing our new design;

FIG. 2 is an opposite side elevational view thereof;

FIG. 3 is an end view from the right hand side of FIG. 1; FIG. 4 is a bottom plan view thereof; and,

FIG. 5 is a side elevational view of a modified filter housing, differing only in the length.
